UNITED STATES PATENT OFFICE.

LESTER M. GRIES, OF DETROIT, MICHIGAN, ASSIGNOR, BY DIRECT AND MESNE ASSIGNMENTS, OF ONE-HALF TO UNITED TOOL AND MANUFACTURING CO., OF DETROIT, MICHIGAN, A CORPORATION OF MICHIGAN, AND ONE-HALF TO MASTER WOODWORKER MANUFACTURING CO., OF DETROIT, MICHIGAN, A CORPORATION OF MICHIGAN.

FLOOR-SURFACING MACHINE.

Application filed November 10, 1925. Serial No. 68,093.

This invention relates to a floor surfacing machine, and has reference to that class of machines including a motor driven sanding drum that may be moved over a floor for sanding and leveling a floor.

My invention aims to provide a surfacing machine that is light in weight, easy to manipulate, properly balanced for a desired floor pressure, and highly efficient for expeditiously and economically removing high spots and irregularities from a floor or similar surface. Structurally the machine may be characterized in the following particulars.

15 First, there is a motor driven sanding drum arranged to be shifted transversely of the machine and driven in any position it may be placed. It is by virtue of this shiftable driven drum that sanding close to 20 a wall may be easily accomplished, thus reducing to a minimum the operation of hand leveling or sanding after the machine has been used.

Second, there is a three-wheel supported 25 carriage or machine body with one of the wheels serving as a caster, and means is associated with the caster for raising and lowering it relative to the carriage or body of the machine, so that a desired degree of 30 pressure may be very delicately controlled and varied by the operator of the machine in connection with the sanding drum. It is by virtue of this caster that the machine may have a two-wheel support to permit of 35 it being readily moved about.

Third, a dust collecting device is associated with the machine and operated from the motor thereof and this device is adapted to remove dust from the sanding drum and 40 the floor in proximity thereto so that the operator may readily observe the level condition of a surface and carry on sanding operations with a minimum interference by dust.

45 Fourth, there is a compact arrangement of parts to which easy access may be had and some of the parts are assembled so as to be readily disassembled to facilitate transportation.

50 The surface machine will be hereinafter specifically described and then claimed, and

reference will now be had to the drawings, wherein

Figure 1 is a perspective view of the floor surfacing machine;

Fig. 2 is an enlarged bottom plan of the 55 same with a few parts removed;

Fig. 3 is a longitudinal sectional view of the machine;

Fig. 4 is a plan of the same, with the 60 motor removed and the sanding drum in horizontal section;

Fig. 5 is another longitudinal sectional view of the machine, partly broken away, and

Fig. 6 is a rear elevation of a portion of 65 the machine.

The machine as now constructed and used includes a substantially rectangular body or frame having side walls 1 and 2 connected by an inclined top wall 3. The side walls 1 and 2 contiguous to the forward edges thereof, are provided with bearings 4 for an axle 5 having wheels 6 at the outer sides of the walls 1 and 2.

Projecting forwardly from the side walls 1 and 2, adjacent the top wall 3 are downwardly inclined arms 7 and 8 which are suitably secured to the walls 1 and 2 with the arm 7 offset relative to the wall 1 by a spacer 9. The outer ends of the arms 7 and 8 are formed with bearings 10 provided with suitable wall buffers 11 and journaled in said bearings are the ends of a drum shaft 12 having a sprocket or power transmission wheel 13 adjacent the bearing 10.

Slidably mounted on the shaft 12 and held for rotation with said shaft by a longitudinal spline or key 14 is a sanding drum 15 of less width than the distance between 90 the arms 7 and 8, so that said drum may be shifted back and forth on the shaft 12 and transversely of the machine. The sanding drum 15 is essentially limited to a length substantially less than the distance or tracking width between the wheels 6, so that one end of said drum may be located adjacent to the plane of one or the other of the side wheels 6, the purpose of which will herein-after appear. The sanding drum is of a conventional design and construction ordinarily including a body 16 supporting

sand paper 17, and the construction of the drum and the manner in which the sandpaper is held so as to be renewed from time to time forms no part of the present invention. It is obvious that there are various types of surfacing drums or devices that can be mounted on the shaft 12 to be rotated thereby relative to a floor or other surface on which the machine is operated.

- 10 The top wall 3 of the machine body is provided with studs 18 by which a motor base 19 may be adjustably mounted on the wall 3. An electric motor 20 is mounted on the base 19, said motor being of a conventional form provided with a switch 21 and leading-in conductors which will permit of the motor being operated from an ordinary electric light circuit or other source of electrical energy. The motor 20 has its armature shaft 22 provided with a sprocket wheel 23 for a chain 24 trained on the sprocket wheel 13 and any other power transmission means may be employed for driving the drum 15 from the motor 20.
- 15 25 The armature shaft 22 has another power transmission wheel 25 that will be herein-after considered.

Mounted on the inner side of the wall 2 is a suction device 26 of a conventional form, preferably an encased fan 27 mounted on a shaft 28, journaled in a bearing 29, carried by the outer side of the wall 2. On the shaft 28 is a power transmission wheel 30 for a belt 31 trained over the wheel 25 so

35 that the motor 20 may drive the fan 27.

The suction device has an intake connection 32 suitably coupled to the neck 33 of a transversely disposed intake nozzle 34, having its ends attached by bosses and nut 40 equipped screw bolts 35 to inturned flanges 36 of the side walls 1 and 2. The nozzle 34 extends transversely of the machine, approximates the length of the shaft 12, extends under the drum 15 in proximity to the floor and provides a wide open mouth to receive dust from the drum and the floor.

45 The suction device 26 has an outlet connection 37 for a stand pipe 38 provided with a return bend 39 from which is suspended a bag or receptacle 40 adapted to receive the dust or other foreign matter drawn into the nozzle 34.

The rear edge of the top wall 3 has a central guide 41 for a shiftable pin 42 which 55 has its lower end provided with a spool 43, an anti-frictional roller bearing 44 and a bearing 45 for a single wheel 46, said bearing and wheel constituting a caster rotatably supported from the pin 42 and adapted to be held normally on the floor by the expansive force of a coiled spring 47 encircling the pin 42 between the spool 43 and the guide 41.

60 Adjacent the guide 41 is a hanger 48 cooperating with a bearing 49 of the side wall 1 in supporting a rock shaft 50 provided

with a fork 51 operatively engaging the spool 43. The outer end of the rock shaft 50 has a crank 52 pivotally connected by a reach rod 55 to a lever 54 having its side arms 55 pivotally mounted between brackets 56, carried by a handle frame 57. The handle frame extends upwardly and rearwardly at an inclination from the machine body or frame and the lower end of the handle frame is suitably mounted in sockets 58, 70 carried by the side walls 1 and 2. The lever 54 is in proximity to the handle bar 59 of the handle frame 57 so that the hands gripping the bar 59 may also grip the lever 54 and hold it in proximity to the handle bar 59 whereby the caster will engage the floor and support the rear end of the machine body somewhat elevated to transfer part of the weight of the machine to the sanding drum and thus produce pressure of 75 said drum on the floor as the machine is moved back and forth during a sanding operation. A suitable clip or holdfast device 60 adjacent one of the brackets 56 will permit of the lever being secured in one 80 position when the caster is elevated against the expansive force of the spring 47 and it is with the caster in this position, as shown in Fig. 3, that the machine can be readily moved about. It can be tilted relative to the axle 5 with the front and rear ends of the machine off of the floor and in such position transferred from one location to another. It is in this connection that the 85 electric motor 20 can be removed to divide the load of carrying the machine from one 90 floor to another if two or more operators are not present to bodily carry the machine.

I attach considerable importance to the 95 arrangement of the caster relative to the sanding drum and the leverage between the 100 caster and the lever, because the lever can be easily held by the same hands on the handle bar of the machine and it is this 105 special control that causes the drum to produce pressure on the floor at the will of the operator, without any tiresome lifting of the handle bar to lower the forward end of the machine. The sanding drum when in 110 operation provides a forward pull for the machine, and it is the hold back power of the operator that produces a pressure in connection with the caster to raise the rear 115 end of the machine and exert pressure on the drum. Obviously this pressure can be 120 very readily controlled and varied by the amount of hold back that the operator applies to the handle bar and lever, which are close enough together to be held at the same time.

I also attach considerable importance to 125 the sidewise movement of the sanding drum because it may be shifted for engagement with a surface, without a sidewise movement of the machine in its entirety. The 130

shiftable drum can be operated very close to a wall on the right hand side of the machine. On a perfectly level surface all three wheels and the drum may engage a floor. 5 If the drum encounters a high spot one side of the drum is raised and the side wheel behind it lifted relative to the floor, throwing almost the entire weight of the machine on that part of the drum in contact with the 10 high spot. This is entirely automatic. The operator feeling the throw, when the weight on the wheel 6 is lessened can transfer his hold to the lever depressing the caster wheel and relatively raising the wheel 6 whereby 15 the entire weight of that side of the machine is carried by the drum and the caster, and the high spot is leveled. Further when a hump in the floor is engaged by the sanding drum and the operator forces down on the 20 caster wheel transferring the weight from a side wheel 6 to the castor wheel and the sanding drum on that side of the machine, there is some tendency to also relatively transfer the weight on the other side 25 of the machine to the drum on that side, where there is no hump in the floor, and consequently the drum might be caused to produce a hollow in the floor. This is prevented, however, because of the restricted 30 length of the sanding drum, there being no abrading portion of the drum adjacent to the wheel on the other side of the machine, therefore any grinding of a hollow spot is 35 impossible. This is all brought about by the slidability of the drum permitting the plac-

ing of the relatively short drum at either side of the machine, and it is in this connection that the operation, as outlined above, is reversible as to the two sides of the machine.

It is thought that the operation and utility of my machine will be apparent without further description, and while in the drawing there is illustrated a preferred embodiment of the machine, it is to be understood 40 that the structural elements are susceptible to such variations and modifications as fall within the scope of the appended claim.

What I claim is:

A surfacing machine comprising a body, 50 side wheels supporting said body intermediate the ends thereof, a caster supporting the rear end of said body, a surfacing drum supported at the forward end of said body, and of a length materially less than the 55 distance between said side wheels, said drum being shiftable from one side of said body to the other side, driving means for said drum, and means on said body adapted to facilitate raising and lowering the rear 60 end of said body relative to said caster, said means being effective in throwing the weight of said body on said caster, said drum and one of said side wheels, the particular wheel depending on the position of 65 said drum relative to said body.

In testimony whereof I affix my signature.

LESTER M. GRIES.
